(No Model.)

S. W. MARTIN.

PUMP.

No. 365,835.

Patented July 5, 1887.

UNITED STATES PATENT OFFICE.

SAMUEL W. MARTIN, OF SPRINGFIELD, OHIO, ASSIGNOR TO MAST, FOOS & COMPANY, OF SAME PLACE.

PUMP.

SPECIFICATION forming part of Letters Patent No. 365,835, dated July 5, 1887.

Application filed January 10, 1887. Serial No. 223,916. (No model.)

To all whom it may concern:

Be it known that I, SAMUEL W. MARTIN, a citizen of the United States, residing at Springfield, in the county of Clark and State 5 of Ohio, have invented certain new and useful Improvements in Pumps, of which the following is a specification, reference being had therein to the accompanying drawings.

This invention relates to improvements in 10 pumps.

My invention consists of a single uniform cylinder having two distinct plunger portions and a water-discharge between said portions, two plunger-rods arranged to travel at un- 15 equal speeds and distances and each having a plunger—one for each plunger portion of the cylinder—and suitable supports for suspending the cylinder below the platform.

My invention further consists of the uni- 20 form cylinder, plunger-rods, plungers, and supports for the cylinder, when combined with a head which rests upon the platform and holds the supports, and which is constructed to allow the rods to pass up through it and to 25 permit the plunger-rods and their plungers to be drawn up from the cylinder and lifted out through the head without in anywise disturbing the fixed parts of the pump.

My invention still further consists of the 30 suitably-supported cylinder and the two plun- gers and their rods arranged so that the upper plunger can be held at rest, to close the upward escape of the water, and the lower plunger be continued in operation, whereby 35 the force-pump is converted into a lift or single-acting pump capable of being actuated either by hand or by power—as by a wind- 40 engine—this latter being principally in view, as the loss of time between the lifting action of the plunger allows time for the wind-engine to regain momentum—a very important practical consideration.

My invention yet further relates to certain 45 features of construction in respect to the sup- porting-head and the actuating-handle and its connection with the plunger-rods and one of said rods and the check-valve.

In the accompanying drawings, forming a 50 part of this specification, and on which like reference-letters indicate corresponding parts,

Figure 1 represents a vertical sectional view of my improved pump entire; Fig. 2, a sectional view of the cylinder, showing the lower plunger and the check-valve therein; Fig. 3, a detail plan view of the top of the head; Fig. 4, a cross-sectional and plan view of the head, showing the flange around the lower end; Fig. 5, a sectional view of the upper end of the head and of the plunger-rods and plungers, showing more clearly the relative sizes of the 60 plungers and the opening in the head; and Fig. 6, a plan view of a fragment of the actuating-handle.

The letter A refers to a well-platform, of any approved type, upon which is mounted 65 the holding or supporting head B. This head is preferably constructed in two vertical parts and substantially like the head shown and described in Letters Patent granted to me De- 70 cember 28, 1886, No. 354,920, for improve- 75 ments in pumps. It differs, however, from that head in two particulars—namely, in being laterally enlarged at C C, to allow the plun- gers and the check-valve to be lifted out and put down through it, and in having a detach- 80 able cap, D, fitted to an opening in the top. This cap on being removed also allows the plun- gers and check-valves to be withdrawn or inserted into place, and while on the head 85 serves to substantially close its upper end, 80 and yet, by reason of the slot E therein, per- 90 mits the plunger-rods to work freely. The parts of the head are held together by bolts, as seen in dotted lines in Figs. 3 and 4, and in 95 seats or bearings F are placed and held the 90 supports G. These supports are, by prefer- ence, of tubular form, and in this instance one of them forms, also, an air-chamber, and the other a discharge-pipe, both being in com- 100 munication with the cylinder at points be- 100

The letter H designates the cylinder, which is uniform, or to all intents and purposes sub- 95 stantially so, in diameter in both of its plun- ger-working portions, of which there are two— 95 one for each plunger. At I the cylinder has short branches, and these branches receive the supports. In the lower end of the cylinder a check-valve, J, of any desired construction, is placed, a packing, K, being provided around 100

the periphery to cause the valve to seat itself snugly into the cylinder, in which case it needs no other fastening. The valve, however, whatever be its construction otherwise, is provided with a part with which the longer plunger-rod is readily engaged, as arms L, having internally-screw-threaded holes at their juncture, into which that rod is entered by disconnecting it from the handle, letting it far enough down and then revolving it. By this means the valve is lifted out of the cylinder, should repairs or other cause require.

The letters M and N respectively refer to the longer and shorter plunger-rods, which respectively carry the lift and force plungers O and P. These plungers work in the respective plunger portions of the cylinder H, and are of any approved construction. The plunger P has a stuffing-box, Q, which prevents the water from rising above it and around the plunger-rod M. It should be noted that the rod N is tubular and that the other rod passes through it. Both are connected to the actuating-handle R, pivoted in standards S of the head, one standard only being shown--M directly and N through an extension, T. The point of connection between the plunger-rod N, through its extension, and the handle is preferably about half the distance between the connection of the rod M and the fulcrum-point of the handle. Therefore the movement of the plunger P is approximately half as fast and half as long as the movement of the plunger O. This overtaking action of the lower plunger causes it to undertake to compress the hydrostatic column between the two plungers, and this being a physical impossibility, being resisted by the natural solidity of water, results in forcing that column out of the cylinder and upward through the discharge-pipe, as G. Then, on the down-stroke, the upper plunger acts upon the water which followed it up into upper-plunger portions of the cylinder, and forces that column out, as it is met and resisted by the column which in the meantime was formed under the lower plunger. Thus the stream is continuous. While it is a fact that double-acting force-pumps are superior as hand-pumps to single-acting lift-pumps, there are yet a class of users who prefer the latter kind of pump when it is to be operated by a wind-engine. Therefore, and to meet the demands of this class, I disconnect the longer rod from the handle and attach it to the pitman of a wind-engine, allowing the upper plunger to remain still and close the upper end of the cylinder, in which instance the pump is converted into a single-acting lift-pump.

If desired, the handle can be bolted to the standard, as at U V, by the bolt which connects it with the longer rod. This insures the upper plunger against accidental movement. The pressure of the water upon the under side of the upper plunger and the weight of the handle will hold the plunger, however.

It will be understood that the cap D is first

removed when it is desired to withdraw the rods, their plungers, and the check-valve.

While I have shown and described the plunger-working portions of the cylinder as of uniform diameter, and while I have shown the upper plunger as having about half the length and speed of movement of the lower plunger, it is obvious that the same result will be obtained if the diameters are changed with respect to each other, provided the length of the travel of the upper plunger with respect to the lower plunger be correspondingly changed, and I would therefore have it understood that such a change is fairly within the scope of this invention. The lower-plunger portion of the cylinder and the lower plunger may of course be extended indefinitely down, as in the case of deep wells, without departing from the invention.

Having thus fully described my invention, what I claim as new, and desire to secure by Letters Patent, is—

1. In a pump, the combination with a uniform cylinder divided into two plunger-working portions and supports connected to it, one of which forms a discharge-pipe and communicates with the cylinder between the said portions, of a shorter tubular plunger-rod and a plunger working in the upper of said portions, and a longer plunger-rod within the other rod, and having a plunger for the lower of those portions, and a pivoted handle, to the shorter arm of which both of said rods are connected, one adjustably, at different distances from the pivotal point.

2. In a pump, the combination, with a uniform cylinder divided into two plunger-working portions and an intermediate portion into which the plungers do not travel, supports connected to the intermediate portion, one an air-chamber and the other a discharge-pipe, and a head upon the platform which holds the said supports, of a tubular plunger-rod having a plunger for one of said plunger portions, and a plunger-rod within the tubular one, and having a plunger for the other of said plunger portions, and a pivoted handle, to the shorter arm of which the plungers are detachably connected, whereby both plungers may be operated at different speeds and distances, or one left to rest and the other operated.

3. In a pump, the combination, with a cylinder divided into two plunger-working portions and an intermediate portion in which the plungers do not work, supports connected to the cylinder, one of which forms a discharge-pipe and communicates with the said intermediate portion, and a suitable head to secure the supports at the platform, of two plunger-rods, each having a plunger, and a pivoted handle to which said rods are connected, one detachably, whereby one rod may be left to rest while the other is actuated to form a single-acting pump.

4. In a pump, the combination, with a head having seats for cylinder-supports and an en-

larged interior passage through which to withdraw the working mechanism, of the tubular-cylinder supports fitted into said seats and held thereby and forming a discharge-pipe and 5 an air-chamber, a uniform cylinder divided into upper and lower plunger portions and open at the top, and plunger-rods, one within the other, and each having a plunger, one lower than the other, and both rods extended 10 up into and above the head and with their plungers adapted to be withdrawn from the cylinder and through the said passage in the head.

5. In a pump, the combination, with a uniform cylinder divided into upper and lower plunger portions and open at the top, and supports connected with the cylinder and extending upward to and connected with a head, of the head having seats which receive and hold 15 said supports, and an interior enlarged passage through which to withdraw the working

mechanism, and plunger-rods, and their plungers extending up to near the upper end of the head and through said passage in the head.

6. In a pump, the combination, with a uniform cylinder open at its upper end, of a head having seats, an enlarged passage, an opening in the top, and a cap detachably fitted to the opening, and supports intervening the cylinder and head, held by said seats and connected with said cylinder, the whole arrangement allowing of the withdrawal through the open end of the cylinder, the passage, and the opening in the head, when the cap is removed, of the lower working mechanism. 25 30 35

In testimony whereof I affix my signature in presence of two witnesses.

Correction in Letters Patent No. 365,835.

It is hereby certified that in Letters Patent No. 365,835, granted July 5, 1887, upon the application of Samuel W. Martin, of Springfield, Ohio, for an improvement in "Pumps," an error appears in the printed specification requiring correction, as follows: In line 100, page 2, the word "adjustably" should be stricken out and the word *detachably* inserted instead; and that the Letters Patent should be read with this correction therein that the same may conform to the record of the case in the Patent Office.

Signed, countersigned, and sealed this 26th day of July, A. D. 1887.
